UNITED STATES PATENT OFFICE.

ELMER J. KELLEY, OF ALGONA, IOWA.

TANK-FILLING DEVICE.

1,153,116.

Specification of Letters Patent.

Patented Sept. 7, 1915.

Application filed February 25, 1914. Serial No. 821,058.

To all whom it may concern:

Be it known that I, ELMER J. KELLEY, a citizen of the United States, residing at Algona, in the county of Kossuth and State 5 of Iowa, have invented new and useful Improvements in Tank-Filling Devices, of which the following is a specification.

This invention relates to tank filling devices, and is especially adapted for use in 10 connection with the gasolene tanks of automobiles and the like, the object of the invention being to provide a novel construction and arrangement of funnel for conducting the gasolene into the storage tank, the said 15 funnel being adapted to be slid into and out of filling position, and when not used for filling, to be housed and concealed out of the way, where it is not liable to be injured.

Under the method now employed in 20 automobiles, it is necessary for the passenger riding in the front seat to descend from the car, before the tank may be filled, and also to remove any robes, baggage, or other articles which may be in the way.

25 By means of the device hereinafter described, it is unnecessary for such person to leave the seat, and furthermore the spilling of gasolene over the seat cushion and floor and other parts of the car is prevented, thus 30 doing away with all of the objectionable features, due to the present method of filling gasolene tanks.

The invention consists in the novel features of construction, combination and arrangement of parts, as will be hereinafter 35 more fully described, illustrated in the accompanying drawings, and pointed out in the claims hereunto appended.

In the drawings: Figure 1 is a vertical 40 sectional view through the front seat and seat support of an automobile, showing the tank equipped with the improved filling device. Fig. 2 is an enlarged sectional view taken at right angles to Fig. 1, and illustrating 45 the construction and operation of the filling device. Fig. 3 is an end view of the tank and filling device. Fig. 4 is a cross section on the line 4—4 of Fig. 2. Fig. 5 is a plan view of the funnel holding inner clip. 50 Fig. 6 is a plan view of the outer clip for holding the funnel in its operative position. Fig. 7 is a plan view, showing the shape of the mouth of the funnel.

55 Referring now to the drawings, 1 designates the front double seat of an automobile, 2 the seat frame, and 3 the gasolene

storage tank, which, as is well-known, is mounted beneath the front seat, the latter forming an inclosing casing for the tank as shown in Fig. 1, said tank being illustrated 60 as equipped with the improved filling device.

The filling device embodies a funnel 4 which is preferably oblong in plan, as shown in Fig. 7, so that it will fit snugly against the end of the tank, when the filling device 65 is collapsed, and occupy the space between the end of the tank, and the adjacent side panel 5 of the automobile body, as shown in Fig. 1, it being intended to provide the body with a removable section 6 for giving access 70 to the filling device, in order to draw the same outwardly for use, and push the same inward, when no longer required. In this way, the filling device is ordinarily entirely concealed from view.

75 The funnel 4 is provided with a downwardly extending neck 7 connected by an elbow or bend 8 with the inner tubular member 9 of a telescopic pipe, the outer section of which is designated at 10. These two 80 telescopic sections may be of any desired diameter and adapted to slide one within the other, as clearly shown in Fig. 2, the outer member being provided at its outer end with a flange 11 which is threaded, as shown at 85 12, to receive a union or gland 13 secured fixedly to the inner tubular section 9, thereby leaving a packing space 14, and adapting the device, as a whole, to act as a stuffing box, and provide a liquid tight joint between 90 the two telescopic sections of the pipe, as will be clearly understood.

The outer section 10 is closed at its inner end by an end wall 15, while the corresponding end of the inner section is left open, as 95 shown at 16.

At an intermediate point, the outer section 10 is provided with a lateral outlet 17 in its lower side, which outlet is opened and closed or covered and uncovered by a relative sliding movement between the inner and outer sections of the telescopic pipe.

In the preferred embodiment of the invention, the tank 3 is provided in its upper side with a semi-cylindrical depression 18 105 forming a gutter, in which the outer member 10 is adapted to seat, said member being securely held and fixed in place by means of a sheet metal cap 19 which is substantially semi-cylindrical in cross section and extends over the section 10, and is flanged at opposite sides, as shown at 20, and sol-

dered, brazed, or otherwise permanently connected to the top wall of the gasolene tank. In this way, the outer telescopic section 10 is securely fixed to the tank, permitting the inner section carrying the funnel 4 to be drawn outwardly and be pushed inwardly with ease.

When the device is contracted, or in other words, when the funnel is pushed inwardly 10 and turned downwardly, as shown in Fig. 1, it is securely retained in said position by means of a forked clip, shown in Fig. 6, and comprising a base 21 secured to the end of the tank 3 at a suitable elevation, as indicated in Fig. 3, and opposite outwardly bowed spring arms 22 adapted to receive and clasp the neck of the funnel, when turned down and pushed inward.

When the funnel is drawn outwardly and 20 turned upwardly to receive gasolene, it is held securely locked in said position by means of another clip, embodying a slideable base 23 having a longitudinal slot, through which pass one or more screws or 25 other fasteners 25, by means of which the plate 23 is secured to the seat frame at such an elevation as to adapt the oppositely bowed spring arms 26 of the clip to embrace and firmly clasp the neck of the funnel. 30 This prevents the funnel from turning in the event of the spout of the gasolene can being allowed to rest too heavily upon the funnel, during the pouring of the gasolene into the filling device.

It will, of course, be understood that the 35 telescopic pipe connected with the funnel and the sections of said pipe may be of any desired length and diameter, and it is preferred to make the same of sufficient 40 strength to support a considerable load, when placed upon the funnel 4, without liability of bending the telescopic sections of

the pipe. The outlet 17 is so located with respect to the extent of movement of the funnel and the inner telescopic section 9 45 that said outlet will be uncovered, by reason of the open end of the inner section 9 passing beyond said outlet, when said inner section is drawn outwardly to place the funnel in its filling position. When the funnel is 50 turned downwardly and pushed back to its collapsed position, the inner section 9 will close and cover the outlet 17, thereby preventing evaporation of the gasolene. 55

What is claimed is:

1. The combination with a liquid holding tank, a casing inclosing the same, of a filling device for said tank, comprising telescopic horizontal tubes, one of which is stationary and the other slideable in the stationary tube and one of which has a lateral outlet communicating with the top of said tank, and a receiving funnel connected to the other tube and set at an angle thereto, and adapted by the movement of the slideable tube to be positioned within or outside of said casing. 60

2. The combination with a liquid tank, and an inclosing casing therefor, of a filling device for said tank, comprising a funnel, a pipe extending at an angle to the base of the funnel and embodying telescopic tubular members having a relative sliding movement and a relative rotative movement whereby the funnel is adapted to be shifted within or outside of said casing, and a clip 70 for holding the funnel in filling position when the pipe is extended. 75

In testimony whereof I affix my signature in presence of two witnesses.

ELMER J. KELLEY.
